PRIMING SYSTEM FOR CENTRIFUGAL PUMPS

Frank S. Broadhurst, Watertown, Mass., assignor to De Laval Steam Turbine Company, Trenton, N. J., a corporation of New Jersey

Application March 8, 1939, Serial No. 260,469

14 Claims. (Cl. 103—113)

This invention relates to priming systems for centrifugal pumps.

In cases where there is no supply of liquid available to prime a centrifugal pump by gravity flow, or where it is undesirable or impossible to prime the pump by the use of an auxiliary water pump, it has been customary to provide the centrifugal pump with an air pump in the same casing to evacuate the main pump and so render it self-priming. A system of this character is very unsatisfactory for several reasons, among which may be mentioned the fact that the centrifugal pump is driven for an appreciable time without priming, which may result in damage to labyrinthine packing, the fact that there is absorption of considerable power by the air pump which is running throughout the operation of the main pump, and the fact that scoring and plugging of the air pump may occur due to grit, dirt, seaweed, etc. in the water being pumped, some of which is passed through the air pump for sealing purposes.

It has also been customary to prime centrifugal pumps on the delivery side, sometimes with the provision of float valves or the like designed to prevent the passage of liquid to a vacuum pump after the centrifugal pump is primed and operating. The valves under such conditions are exposed to high pressures and are liable to damage by impact and blocking by solid or semi-solid material jammed against them, for example, in the handling of sewage.

In general pumping, and particularly in the pumping of driven walls, air is carried into the centrifugal pump with the liquid. This air is separated by the centrifugal action of the pump and accumulates adjacent the shaft. When the accumulation reaches such extent as to substantially cut off the intake passages, the pump will lose its prime and with previous priming systems it was necessary to shut down the pump, re-prime, and then restart the pumping operations.

In my application Serial No. 11,867, filed March 19, 1935, there are disclosed priming arrangements for centrifugal pumps which overcome the aforementioned objections to prior priming arrangements. The present invention relates to priming systems of this general type in which priming is effected by evacuation of the suction side of a centrifugal pump. The present invention, however, involves various improvements on the systems described in my prior application whereby the operation of the vacuum pumps is still further reduced, normal operation, even though it involves a considerable accumulation

of gas, being accompanied with no operation of the vacuum pump or pumps unless abnormally high quantities of gas enter the system. Under normal conditions, the evacuation only takes place in the initial priming of the system on starting. Thereafter accumulated gas is removed automatically by the action of the centrifugal pump itself.

Subsidiary to the broad object of the invention just indicated are various secondary objects having as their ends the proper rapid and reliable operation of the priming system to take care of modern centrifugal pumping installations which are designed to operate automatically over long periods with little or no attention. Specifically, the subsidiary objects of the invention relate to the provision of arrangements for taking care of abnormal gas accumulation, for handling water carrying sediment or floating material, and for maintaining proper operation despite surges attending unusual conditions in the supply or discharge lines. Additionally, provision is made for the operation of pumps in parallel or the operation of pumps receiving their liquid from different supplies, and particularly under circumstances in which any one or more of a series of pumps primed by a common system may be subjected to an abnormal accumulation of gas. In such case the other pump or pumps may relieve it of the gas accumulation without a restarting of the vacuum pumping means.

The primary and specific objects of the invention will be clear from the following description read in conjunction with the accompanying drawings, in which:

Figure 1 illustrates diagrammatically a preferred embodiment of the invention applicable for general pumping use;

Figure 2 is a vertical sectional view showing the association of gas removing means and control means with the casing of the centrifugal pump of Figure 1;

Figure 3 is a wiring diagram showing the electrical connections in the arrangement of Figures 1 and 2;

Figure 4 is a view similar to Figure 1, but illustrating a modified form of the invention;

Figure 5 is a similar view, partly in section, but showing the invention applied to the priming of a plurality of centrifugal pumps;

Figure 6 is a diagrammatic view illustrating still another modification of the invention particularly applicable to the pumping of liquid containing relatively large quantities of gas or dirt,

for example, as occurs in the pumping of driven wells; and

Figure 7 is a diagrammatic view illustrating a further modification applicable particularly to gravel packed wells.

Referring first to the modification of Figures 1, 2 and 3, there is illustrated therein a motor 2 arranged to drive a centrifugal pump 4 receiving liquid through the pipe 6 from a source such as, for example, a sump 8 located below the level of the pump. Figure 2 shows a section of a portion of the upper casing of the centrifugal pump, which, in the illustration is a double suction pump, the suction bells being indicated at 10 and the discharge volute being indicated at 14, though it will be obvious that the invention is applicable to a single suction pump and to multiple stage centrifugal pumps as well as the type illustrated. The impeller of the pump indicated at 12 operates in the pump casing of which the discharge volute 14 is a part. The pump is associated with the conventional valves including the usual discharge check valve.

At the top of each of the suction bells there is provided a connection to a pipe 16, preferably of substantial diameter. For example, this may have a diameter of 1½ inches. A large diameter pipe is desirable at this point to provide for the free upward passage of gas. The pipes 16 communicate with a chamber 18, which may take the form of a rectangular box. Extending from the top of this chamber 18 are tubes 20 passing through the pipes 16 and terminating as indicated at 22 closely adjacent the shaft of the centrifugal pump.

Extending from the top of the chamber 18 there is the evacuating passage 24 communicating with a water jet air pump indicated at 28, there being interposed in the connection 24 a check valve 26 adapted to prevent reverse flow of fluid back to the chamber 18. The water jet air pump is provided with supply water under pressure through a passage 30 controlled by a valve 32 actuated by a solenoid indicated at 34, the valve being closed when the solenoid is actuated. The discharged liquid and gas from the water jet air pump are discharged through conduit 36.

Supported in a holder at the top of the chamber 18 are electrodes 38 and 40, the former of which is substantially longer than the latter. These two electrodes are the control electrodes for a relay which is illustrated as of the well-known Bender-Warrick induction type. This type of relay is provided with an A-shaped core indicated at 42 having a coil 44 on its crossbar portion grounded at one end and connected at its other end to the electrode 40. The upper connecting element of the core is provided with a coil 46 permanently connected to an alternating current power line. The legs of the core are adapted to attract an armature 48, which is conventionally illustrated as adapted to close a single contact at 50, and thereby connect the electrodes 38 and 40 together, and a pair of contacts 52 adapted to cause the energization of the solenoid 34, which controls the valve 32, and also effects the removal of a short circuiting connection for the no-voltage release of the starter 56 for the pump motor 2, this being accomplished through a suitable relay, which is not shown. The relay may be conveniently enclosed in a box 58 secured to the chamber 18 and connections made through an electrical outlet box indicated at 60.

Operation of the modification so far described is as follows:

Assuming that the pump is unprimed, the armature 48 will not be attracted by the field member 5 of the relay because the flux produced by the coil 46 will have its magnetic circuit completed through the crossbar carrying the open-circuited coil 44. The solenoid 34 will, therefore, be deenergized and the valve 32 will be opened. The no-voltage release coil of the starter will be deenergized, and consequently the motor 2 cannot be started.

To start the operation of the unit, water from the air pump supply is caused to flow through the conduit 30, thereby drawing a vacuum in chamber 18. Due to this action, the liquid will be lifted through the inlet 6 into the centrifugal pump (the usual check valve on its delivery side being closed), and will rise through both sets of tubes 16 and 22 immersing the lower end of the electrode 38. Nothing will happen, however, since the electrode 38 is open-circuited at 50. As soon, however, as the liquid reaches the level of the electrode 40, the coil 44, now acting as the secondary of a transformer, will have its circuit completed through the liquid to ground. Consequently, a counter-magnetomotive force is created opposing the flux through the crossbar so that the flux will tend to take a path through the armature 48, attracting this armature and closing the contacts at 50 and 52. As soon as the contact at 50 is closed, electrode 38 is thrown in parallel with the electrode 40 and will additionally tend to maintain the closed condition of the relay. At the same time, the solenoid 34 is energized, closing the valve 32 and removing the short circuiting connection from the no-voltage release of the motor starter.

The pump is now primed and the motor is ready to start. Starting may be effected by a hand control of the starter; or, alternatively, the arrangement may be readily made such that upon energization of the no-voltage release coil the motor will start automatically. Since the specific arrangements for automatically starting a motor are no part of the present invention, this may be considered as embodied in the diagrammatic illustration of the starter at 56.

Before passing to the centrifugal pump operation and priming considerations, it might be here noted that the arrangements of the two electrodes 38 and 40 prevent unstable operation since, though the stopping of the vacuum producing means is not effected until the electrode 40 is submerged, the vacuum producing means will not be restarted until the liquid level drops below the lower end of the electrode 38, inasmuch as this electrode, through the closure of its circuit at 50, acts as a holding control, maintaining the armature 48 in its attracted position. The height between the lower ends of the two electrodes defines a region through which fluctuations of liquid level may occur without disturbance to the system. This distance should be made such that normal fluctuations in liquid level due to surges or other causes will not result in restarting of the vacuum producing means or stoppage of the driving motor 2. On the other hand, whenever the liquid drops below the level of the electrode 38, the motor 2 will immediately stop, due to short circuiting of the no-voltage release, and will not then restart until the electrode 40 is submerged.

The action just described would obviously be

unsatisfactory if continuous priming, i. e., continuous removal of gases did not take place independently of the water jet air pump 28. As a matter of fact, the arrangement of the pipes 16 and 20 effects continuous removal of normal amounts of gas which might accumulate by the action of the centrifugal pump itself.

Assume that priming has taken place with the resulting rise of the liquid to the level of the electrode 40 and that the motor 2 has then been started either manually or automatically to drive the centrifugal pump. The check valve 26 will have closed upon interruption of flow of the air pump operating liquid through 30 by the action of valve 32.

It will be noted that the lower end of the electrode 40 is substantially below the upper ends of the tubes 20, providing a substantial gas space. As the liquid flows into the impeller from the suction bell, a sufficiently high velocity is created due both to the approach and the rotation of the liquid in the bell by the shaft as to create a substantial ejector action at the lower ends 22 of the tubes 20 where they approach the shaft. A partial vacuum is thus produced which in typical installations may be of the order of about 4 feet of water. The creation of this partial vacuum removes the gas from the space at the upper end of the chamber 18 in such fashion that the gas is entrained in fine bubbles in the water in the suction bell and is hence carried without separation to the impeller 12 to be discharged thereby. This provides a rise of liquid from the suction bells through the pipes 16 and within the chamber 18 to the upper ends of the tubes 20, whereupon during continued operation there occurs a recirculation of liquid from the suction bells into the chamber and thence through the tubes 20 to their lower outlets adjacent the shaft. A differential pressure of the amount indicated is thus continuously maintained between the upper end of each of the suction bells and the lower ends 22 of the tubes 20. If gas accumulates and floats upwardly through the pipes 16, it will be removed immediately by reason of this ejector action and consequently the liquid level during normal operation with normal amounts of gas entering the device will remain near the upper ends of the tubes 20.

If larger amounts of gas enter with the incoming liquids, it is possible that this gas may be separated centrifugally within the suction bells, with the result that the lower ends of the tubes 20 may be surrounded by gas rather than liquid. As soon as this occurs, the ejector action at the tubes 20 will cease and consequently an equalization of pressure will occur in the system subject only to the centrifugal action which takes place. The static head of the liquid, however, above the suction bell will cause the gas surrounding the lower ends of the tubes 20 to be forced upwardly therethrough into the upper portion of the chamber 18, producing a drop in the liquid level therein. Since the chamber 18 has a volume substantially greater than the total volume of the suction bells, it will be obvious that the liquid level will not drop to any great extent before the lower ends of the tubes 20 are again exposed to liquid with a renewal of the ejector action. The accumulated gas will then be rapidly drawn off in a fine state of subdivision so as to pass into the impeller without reseparation, and consequently the liquid

level will be restored to normal at the level of the upper ends of the tubes 20.

As a result of the ejector action, and also the possibility of removal of centrifugally separated large quantities of gas, the continuous removal of accumulated gas takes place with the result that only under the most abnormal conditions will the liquid level in the chamber 18 fall below the lower end of electrode 38 to close down the system. Under such conditions, as soon as the electrode 38 is cleared by the liquid, the jet air pump will reprime the system and, if the motor 2 is automatically controlled, it will restart as soon as the electrode 40 is submerged.

15 If the motor 2 is not arranged to be self-starting, then it is desirable to have some signal indicate the stoppage of the system to an operator, who may thereupon promptly restart it if the cause of the loss of prime has been corrected. 20 In the case of bilge pumps it is desirable to have manual starting since the failure of prime will be generally due to the removal of all the liquid in a bilge, and necessity for restarting would not be expected to occur for a long interval. The tubes 20 preferably extend upwardly near the top of the chamber 18 so as to leave a minimum air space at the top of the tank preventing drop of liquid level to any substantial degree upon the occurrence of surges.

25 While reference has been made to priming with the motor stopped (as is generally desirable with centrifugal pumps) it will be clear that the priming system will operate just as well with the motor running as may be the case in some instances where such type of priming is desirable and the centrifugal pump is of a type which will not be damaged by dry running for substantial periods of time. If the motor is running when initial priming is taking place, the removal of centrifugally separated gas will take place as indicated above, with the ultimate result that the conditions heretofore described will be established.

30 The reason for the relatively large diameter of the pipes 16 will be obvious. A large passage for the upwardly floating gas is desirable for its rapid accumulation at the top of the chamber 18. This should be free to occur without any possibility of having the passages through pipes 35 16 contain "plugs" of gas. On the other hand, the tubes 22 may be of relatively small diameter, since then a better ejector action is secured with a resulting fine dispersion of the gas so that it will be carried along by the liquid without again separating in the suction bells.

35 In Figure 4 there is illustrated a modification of the arrangement just described which is essentially the same as that modification except for provision for priming under conditions when a high pressure water supply is not available for actuating the water jet air pump. In this modification of Figure 4, the vacuum connection 24 is connected through the check valve 26 to a water jet air pump indicated at 62. This is arranged to discharge into a vessel 64, the discharge taking place through the pipe 66 opening within a chamber separated by a baffle 68 so as to provide for the more ready separation of the exhausted gas and prevention of passage of this gas to a centrifugal circulating pump indicated at 70 arranged to supply the water to the jet pump for its operation. The gas removed by the 40 ejector after separation may pass out of the vessel at 74. The centrifugal pump is driven by 45 a motor 72 controlled by a starting box 75 which

is automatically controlled by the same type of electrical connections as were used for the control of the solenoid 34 in the previously described modification. In this case, however, the starting box is so arranged under relay control that the motor 72 will be started whenever the longer electrode 38 is uncovered by liquid and will be stopped only when the electrode 40 is submerged. Thus the motor 72 and the water jet air pump will be actuated only when it is necessary to draw a vacuum under the conditions described in connection with the previous modification.

The two modifications heretofore described will make clear the more general application of the invention to the use of various vacuum producing devices for effecting priming. Any suitable type of wet air pump might be substituted for the water jet air pumps described, and may be subjected to suitable control by the electrodes 38 and 40, as will be obvious. The vacuum connections illustrated, however, would necessitate a wet type of air pump. A dry type could not be directly used because the connections are of such nature that liquid may enter the pump. If a dry type of pump is to be adopted, then provision must be made to prevent passage of liquid to the air pump. Arrangements for this will now be described in connection with the modifications of Figures 5 and 6.

Considering first the modification of Figure 5, there is illustrated therein an arrangement for the priming of a plurality of centrifugal pumps by means of a dry type vacuum pump. In this modification there are illustrated at 76 and 76' motors driving centrifugal pumps 78 and 78', which may be of any suitable type as indicated above. These pumps receive their liquid through the conduits 80 and 80', respectively.

The pump 78 has extending through its suction bells and closely adjacent the shaft a pair of tubes 82 corresponding to the tubes 20 of the previously described modification. This pump also has communicating with the tops of its suction bells tubes 84 which correspond to the tubes 16 of the previous modification, but which are illustrated as not concentrically arranged with the tubes 82. (It will be understood that the concentric arrangement of the previous modification plays no particular part in the operation and merely serves for convenience of mounting of a small chamber such as 18.) The tubes 82 are preferably of small bore and the tubes 84 of large bore for the reasons indicated above in connection with tubes 20 and 16. The pump 78' is provided with tubes 82' and 84', respectively similar to tubes 82 and 84.

The tubes 82 and 82' are connected to a header 86 which is joined by tubing 88 to a wet chamber 90 located at a level substantially above the pumps. The connection 88 enters this wet chamber substantially above its bottom as indicated. The tubes 84 and 84' are joined to a header 92 which is connected by a tube 94 with the bottom of the wet chamber 90. The wet chamber 90 may be built as a unit with a dry chamber 100, separation being provided by a wall 101, though it will be obvious that chambers which are structurally completely separate may be provided. A valve 96 controls flow of gas from the chamber 90 to the chamber 100, this valve receiving gas from the chamber 90 through a tube 98, which opens at the extreme top of the chamber 90 to thereby avoid the possibility of the passage of any substantial quantity of liquid into the cham-

ber 100. The valve 96 is controlled by a float 102, being open when the float is in its lower position and closed when the float reaches an upper position in which it is arrested by a stop 104. The arrangement is preferably such that the tube 88 communicates with the chamber 90 above the top of the float 102 when in its arrested position so that when liquid rises to the level of the tube 88 the float will be held by its full buoyant force against the stop 104 to thereby insure that it will not bob up and down with slight fluctuations in the liquid level. Preferably it will have closed the valve 96 completely substantially before rising to its ultimate level.

Accumulation of liquid in the chamber 100 cannot be completely prevented since it will be carried over not only as fine spray, but more particularly in the form of vapor which may condense in the tank 100. Since, as in this case, the pumps may be of a type which cannot permissibly handle an aqueous liquid without damage, provision should be made for removing any accumulated liquid from the tank 100 from time to time. In the present case, this takes the form of a water jet ejector 108 connected at 106 to the bottom of the tank 100 with the interposition of a check valve 107 adapted to close and maintain the vacuum in the tank 100 when the jet pump is not operated. The supply line for the jet pump is indicated at 110 and may be manually controlled. The discharge is through the pipe 112 into the wet chamber 90. Under usual conditions of operation, this jet pump need be operated only for very short periods at long intervals. A gauge glass may be provided to indicate any accumulation of liquid in the tank 100.

A vacuum is maintained within the chamber 100 through connections 114 and 114' containing check valves 115 and 115' by means of vacuum pumps 118 and 118' driven by motors 116 and 116'. A pair of these vacuum pumps 118 and 118' is illustrated, since some installations require a very great factor of safety and it is desirable in such case to duplicate the vacuum pump to insure against failure of operation. The vacuum pumps in the present case are illustrated as of the "Imo" type, i. e., comprising a plurality of screws arranged to be motor driven and sealed to provide air pumping passages by means of oil contained in a tank indicated at 120. Pumps of this type are positive pumps capable of handling large quantities of air which may be separated from the recirculating oil by means of a screen arrangement indicated at 122 and thence pass outwardly through a pipe 124 which may pass to a device for further insuring separation and avoiding loss of oil. These pumps, while using oil for sealing purposes, would be classified as dry pumps, since they are apt to be damaged by a non-lubricating liquid such as water.

The motors 116 and 116' are under the control of vacuum switches 126 and 128 communicating with the tank 100 and controlling the motors through a motor starting box 130. The two vacuum switches are again provided for safety purposes. One of them, for example, may be effective to start the motors at a vacuum of 18 inches of mercury and stop the motors at 26 inches of mercury, while the other may start the motors at a vacuum of 16 inches and stop them at 26 inches. Thus the former will normally be the controlling switch, while the latter serves to effect its control only under emergency conditions.

Both of these should be of the snap type, as indicated, to avoid any instability of operation.

A low water cutoff indicated at 132 may be used for control of the centrifugal pump motors to prevent their starting before the liquid rises to a predetermined level in the tank 90 and to cause them to stop if the liquid drops below such level. This low water cutoff may be either float controlled or may be of the electrode controlled type previously described.

In the operation of the modification of Figure 5, assuming the centrifugal pumps stopped, the priming may be initiated by closing the main switch controlling the motors 116 and 116'. The valve 96 will now be opened due to the lower position of the float 102 and hence a vacuum will be drawn on the system causing the liquid to rise in the centrifugal pumps through the tubes 82 and 84, headers 86 and 92 and then the tank 90. As the rise of liquid continues, the low water control 132 will be actuated to either start automatically the motors 76 and 76' or to render it possible to start them manually. Eventually the float 102 will close the valve 96, thus preventing further entrance of gas into the tank 100, whereupon the pumps 118 and 118' will continue to operate until the vacuum switches stop them by reason of the drawing of a high vacuum in the tank. As operation proceeds, the ejector action described in connection with the previous modification will take place at the lower ends of the tubes 82 and 82', resulting in further evacuation of gas from the chamber 90 and rise of liquid to force the float 102 against its stop 104. Thereafter the liquid will rise to the level of the connection 88 and recirculation will then take place upwardly through the tubes 84 and 84' and downwardly through the tubes 82 and 82'. As small normal quantities of gas accumulate in the tank 90 this gas will be drawn off without producing any dropping of the float 102 and, therefore, without opening the connection to the vacuum tank 100.

In the event that air is centrifugally separated in considerable amount within the intake bells of either of the pumps, this air will first escape through the tubes 82 into the tank and will then be drawn out gradually by the ejector action as in the case of the modifications previously described. Under such circumstances, if the tank 90 is of considerable size, there may still be no opening of the valve 96. A substantial amount of air may flow into the tank 90 without causing the float 102 to move away from its stop.

In the event that a plurality of pumps are provided, it will be seen that all contribute to the maintenance of the primed condition of any one of them. Consequently, even though one may receive a substantially large quantity of gas, this gas will be rapidly removed by the action of the others, in fact without ever reaching the tank 90, since the ejector action in a companion pump or pumps will merely cause recirculation of the gas upwardly through the tubes 82 in the pump from which the gas flows, into the header 86 and downwardly through the tubes 82 of the pump or pumps which continue to operate normally.

As a result of the arrangement described, the vacuum pumps 118 and 118' will operate usually only in starting up the system. They will resume operation only if such a large quantity of gas enters the tank 90 as will produce an opening of the valve 96 and reduction of the vacuum to an extent sufficient to throw one of the vacuum switches. By reason of the fact that the system

may operate for very long periods taking care of normal gas operations without operation of the vacuum pumps an extremely economical arrangement is secured. Under such conditions, there is, of course, correspondingly little accumulation of water in the bottom of tank 100, and removal of this by the water jet air pump 108 need be effected only at long intervals.

At this point it may be remarked that the tubes 82 or 20 may be so formed at their lower open ends as to secure various efficiencies in the ejector action. In the event that they open in a direction perpendicular to the shaft, the ejector action is quite sufficient for most purposes, being, for example, such as to produce a vacuum of the order of four feet of water relative to the pressure in the suction bell. At the same time, they will remove rapidly any gas which may accumulate centrifugally about the shaft. A more effective ejector action may be secured if the lower ends of the tubes 82 open closely adjacent the shaft, but in the direction of circulation about the shaft, thus giving rise to a Pitot tube action. Under such conditions, however, the separation of centrifugally accumulated gas is not as rapid as before because of the ejector action of the rotating gas. Such ejector action, however, is far less than that secured by the passage of the liquid past the lower ends of these tubes.

In Figure 6 there is illustrated still another modification of the invention particularly adapted to the case of the pumping of water or other liquid containing sediment and relatively large quantities of gas, for example, in the pumping of driven wells. In this arrangement a motor 134 drives a centrifugal pump 136, the intake passage 138 of which receives liquid from the so-called sand tank 140, which is connected through passage 142 with the supply. Within the chamber 140 are baffles 144 designed to prevent the passage of sediment to the pump, the tank being provided in conventional fashion with a clean-out opening (not shown). The centrifugal pump 136 is provided with a pair of tubes 146 extending through its suction bells to a point adjacent the shaft, these tubes 146 corresponding to the tubes 20 and 82 of the previous modifications. In this case, however, there are no tubes provided corresponding to 16 and 84, inasmuch as the tank 140 serves for the separation of any gas which, in the absence of the tank 140, might separate in the suction bells of the pump. The tubes 146 are connected through a common tube 148 to the upper end of the tank 140, the head of which is indicated at 141, there being built as an upward continuation of it a vacuum tank 156.

Opening just below the top 141 of the tank 140 is a tube 150 communicating through a valve 152 with the pipe 154 entering the vacuum tank 156. The valve 152 is similar to the valve 96 previously described, and is controlled by a float 158 the upward movement of which is limited by a stop 161 so that when liquid rises to the height of the tube 148 the float 158 will be against the stop 160 and substantially completely immersed so as to avoid fluctuations of its level and possible opening of the valve 152. The valve 152 is closed substantially before the float 158 engages its stop.

From the bottom of the tank there is the passage 160 controlled by check valve 162 and communicating with the water jet pump 164 receiving a supply of water under pressure through 166 and discharging at 168 into the tank 140. As in the case of the vacuum pump 108 previously de-

scribed, this vacuum pump serves for the removal of moisture which may accumulate in the bottom of the vacuum tank due to the passage of spray thereto or condensation.

From the top of the vacuum tank there extend vacuum lines 172 and 172' containing check valves 170 and 170' and communicating respectively with high vacuum pumps driven by motors 174 and 174', this arrangement corresponding to that described in connection with the modification of Figure 5.

For the control of the motor 134 there may be provided the level switching arrangement 175 connected to the tank 140 at 178 and 180. Instead of a float controlled switch there may be provided an electrode type arrangement similar to that illustrated in the first modification. In any event, a suitable switching arrangement is provided to insure either automatic starting of the motor 134 when the liquid rises to a predetermined level or, alternatively, a possibility of manual starting. At the same time, the switching arrangement must provide for stopping of the motor 134 in the event of abnormal drop of the liquid level.

The vacuum pumps are under control of vacuum switches 182 and 184 connected to a common relay or motor starter 186. These switches may be of the same type and act in precisely the same fashion as the switches 122 and 128 of the modification of Figure 5.

The above indication of the correspondence of elements of Figure 6 with those of Figure 5 will make clear the nature of the operation of the modification of Figure 6. The only substantial difference is that the circulation effected by the ejector action at the lower ends of the tubes 146 will be from the tank 140 through the tube 148 and tubes 146 after the liquid level rises to the level of 148. Any air accumulating in the tank 140 will be drawn off through the tube 148. As in the previous modification, this takes care automatically of any normal accumulations of air and the float 158 will be permitted to drop to open the valve 152 only upon an abnormal accumulation of air in the tank 140. If this occurs, then the air will pass to the vacuum tank 156, where substantial accumulation will result in renewed operation of the vacuum pumps. Under normal conditions, even with considerable accumulation of air in the tank 140 the vacuum pumps will not operate except in the initial priming of the system. If any sufficient amount of air should find its way into the centrifugal pump so as to be centrifugally separated in the suction bells the tubes 146 will take care of this air by permitting it to pass into the upper end of the tank 140. As soon as the ejector action is renewed, this air will then be removed by the centrifugal pump.

In Figure 7 there is illustrated a modification of the invention applied to a gravel packed well of conventional type. Such a well comprises a casing 190 which has a lower screen portion 192 through which water may enter. Surrounding the screen portion of the well and in general extending upwardly to the surface, there is a packing of gravel indicated at 194. There extends downwardly from the surface an outer shield indicated at 198 which is sealed with concrete to a level below the normal static water level, indicated at 200. In general, this static water level is less than five feet to the center line of the pumps.

Pumping is effected by connecting at 202 to 75

the casing one or more centrifugal pumps indicated at 204, driven by one or more motors 206 and arranged to discharge through conventional check valves 208.

5 In accordance with the present invention, the casing 190 is continued to a substantial height above the intakes of the pumps, say about five feet above the pump house floor. The extension or the casing as well as the casing itself may be 10 two or more feet in diameter so that there is provided by the extension 210 a quite large diameter which may act as a reserve pump for available liquid to prime the pumps in the event of any large influx of air.

15 The extension 210 is provided with a cover 212 from which extends a pipe 214 to a vacuum tank 216, having wet and dry compartments 218 and 220, respectively. Since this tank and its various 20 associated parts may be identical with the tank assembly heretofore indicated at 100 in Figure 5, the various parts thereof need not be described.

25 The dry portion 220 of the tank is connected to vacuum pumps 222, as heretofore described, under control of vacuum switches, and the wet compartment 218 is connected through pipes 224 to tubes 226 closely approaching the pump shafts as previously described, so as to give rise to an ejector action during operation of the pumps.

30 The operation of this modification is quite similar to that of the modifications previously described. The vacuum pumps create a vacuum to cause the supply liquid to rise into the wet chamber 218 until the float therein closes off the vacuum communication. Thereafter, as the pumps

35 run, they maintain by ejector action the vacuum above the level of the liquid in the wet compartment, causing the float valve to rise against its stop and produce ultimately a circulation of liquid from the extension 210 of the casing 40 through the wet compartment and to the pumps through the pipes 224 and 226. Thus accumulation of air in the extension 210 is drawn off without having the communication between the tanks 218 and 220 reopened under normal circumstances.

45 Even a sudden large influx of air will not interfere with operation by causing the centrifugal pumps to lose their prime because of the large volume provided by the casing extension. Any such large amount of air which may enter the casing will be taken care of gradually by the ejector action and, of course, by the volume pumps if the influx is such as to cause the float valve to open. A suitable low level safety arrangement may be provided to stop the centrifugal pumps in case the liquid level becomes 55 dangerously low within the casing extension.

60 It will be understood that the various elements of the device, particularly the vacuum pumping arrangements, may take various forms. For example, water jet ejectors or even steam jet air pumps may be used throughout the arrangement, or either wet or dry types of mechanical vacuum pumps may be used. In the event that wet types are used, no precautions need be taken to avoid the passage of water to the pumps, and accordingly the general type of arrangement indicated in Figure 1 can be adopted. The adaptation of this to a sand chamber or tank of the type indicated in Figure 6 will be obvious, as will also be its adaptation to the priming of a plurality of pumps.

65 It will be noted that the various modifications described above have in common the characteristic of maintaining above the pump a quite substantial supply of liquid so that, in effect, the

pump is maintained primed by what is during operation a flooding arrangement. Thus, while the invention contemplates a suction priming system, it is differentiated sharply from such priming systems as merely raise the liquid to the level of the pump, but which would permit the pump to lose its prime in the event of slight drop of liquid level.

What I claim and desire to protect by Letters Patent is:

1. In combination, a centrifugal pump; means providing a chamber connected to the intake passage of the centrifugal pump; means for evacuating said chamber to raise liquid therein to a level above the intake passage to thereby prime the pump; means controlled by rise of liquid in said chamber to a predetermined level to stop the evacuation of said chamber by said means; and means connected to said chamber and subjected to an ejector action of liquid being handled by said pump to cause rise of liquid in said chamber substantially above said predetermined level, said last means comprising a tube opening closely adjacent the shaft of said pump and subjected to the ejector action of liquid adjacent said shaft, and arranged to provide flow of centrifugally separated gas adjacent the shaft to said chamber during its evacuation by the first mentioned evacuating means.

2. In combination, a centrifugal pump; means providing a chamber connected to the intake passage of the centrifugal pump; means for evacuating said chamber to raise liquid therein to a level above the intake passage to thereby prime the pump; means controlled by rise of liquid in said chamber to a predetermined level to stop the evacuation of said chamber by said means; means connected to said chamber and subjected to an ejector action of liquid being handled by said pump to cause a rise of liquid in said chamber substantially above said predetermined level; and means for effecting further evacuation of said chamber by the first mentioned evacuating means only when said liquid level falls substantially below the level to which it rises under the action of said last named means.

3. In combination, a centrifugal pump; means providing a chamber connected to the intake passage of the centrifugal pump; means for evacuating said chamber to raise liquid therein to a level above the intake passage to thereby prime the pump; means for stopping the evacuating action of the last means when the liquid has been so raised; means connected to said chamber and subjected to an ejector action of liquid being handled by said pump to maintain a partial vacuum in said chamber after evacuation by said evacuating means ceases; and means for effecting further evacuation of said chamber by the first mentioned evacuating means only when the liquid level drops substantially below a normal level attained under the action of said means subjected to ejector action of liquid.

4. In combination, a centrifugal pump; means providing a chamber connected to the intake passage of the centrifugal pump; means for evacuating said chamber to raise liquid therein to a level above the intake passage to thereby prime the pump; means controlled by rise of liquid in said chamber to a predetermined level to stop the evacuation of said chamber by said evacuating means; and means connected to said chamber and subject to an ejector action of liquid being handled by said pump to maintain a partial vacuum in said chamber, said last means

comprising a tube opening closely adjacent the shaft of said pump and subjected to the ejector action of liquid adjacent said shaft, and arranged to provide flow of centrifugally separated gas adjacent the shaft to said chamber during its evacuation by the first mentioned evacuating means.

5. In combination, a centrifugal pump; means providing a chamber connected to the intake passage of the centrifugal pump for accumulation of gas contained in the liquid being pumped; means for evacuating said chamber to raise liquid therein to a level above the intake passage to thereby prime the pump; means connected to said chamber and subjected to an ejector action of liquid within the intake passage and being pumped to maintain a partial vacuum in said chamber, said last means comprising a tube opening closely adjacent the shaft of said pump and subjected to the ejector action of liquid adjacent said shaft; and means effective to close communication between the chamber and said evacuating means when liquid in the chamber reaches a predetermined level below the level of connection with the chamber of the means subjected to said ejector action of liquid.

6. In combination, a centrifugal pump; means providing a chamber connected to the intake passage of the centrifugal pump; means for evacuating said chamber to raise liquid therein to a level above the intake passage thereby to prime the pump; means controlled by rise of liquid in said chamber to a predetermined level to stop the evacuation of said chamber by said means; and controlled by drop of liquid to resume evacuation of said chamber by said means; and means connected to said chamber and subjected to an ejector action of liquid being handled by the pump to evacuate the chamber to maintain the liquid therein normally at a level above that at which evacuation is resumed by said evacuating means.

7. In combination, a centrifugal pump; means providing a chamber connected to the intake passage of the centrifugal pump; means for evacuating said chamber to raise liquid therein to a level above the intake passage thereby to prime the pump; means controlled by rise of liquid in said chamber to a predetermined level to stop the evacuation of said chamber by said means; and means connected to said chamber and continuously subjected to an ejector action of liquid being handled by said pump to effect continuous removal of gas accumulating in said chamber to maintain at least said predetermined level of liquid which is effective to stop evacuation.

8. In combination, a centrifugal pump; means providing a chamber connected to the intake passage of the centrifugal pump; means for evacuating said chamber to raise liquid therein to a level above the intake passage thereby to prime the pump; means controlled by rise of liquid in said chamber to a predetermined level to stop evacuation of said chamber by said means; and additional evacuating means connected to said chamber and effective when the pump is handling liquid to cause a rise of liquid in said chamber substantially above said predetermined level and to the connection of said additional evacuating means with the chamber so that liquid flows from the intake passage through the last named means during operation of the pump.

9. In combination, a centrifugal pump; means providing a chamber connected to the intake passage of the centrifugal pump; means for evacuating said chamber to raise liquid therein to a level above the intake passage thereby to prime

the pump; means controlled by rise of liquid in said chamber to a predetermined level to stop evacuation of said chamber by said means; and additional evacuating means connected to said chamber and subjected to an ejector action of liquid being handled by said pump to cause a rise of liquid in said chamber substantially above said predetermined level and to the connection of said additional evacuating means with the chamber so that the liquid is circulated from the intake passage through the last named means during operation of the pump.

10. In combination, a centrifugal pump; means providing a chamber connected to the intake passage of the centrifugal pump; means for evacuating said chamber to raise liquid therein to a level above the intake passage thereby to prime the pump, said evacuating means comprising a vacuum tank connected to said chamber; means for closing the connection between the chamber and vacuum tank when the liquid rises to a predetermined level in said chamber; and means connected to said chamber and continuously subjected to an ejector action of liquid being handled by said pump to effect continuous removal of gas accumulating in said chamber and to maintain at least said predetermined level of liquid therein.

11. In combination, a centrifugal pump; means providing a chamber connected to the intake passage of the centrifugal pump; means for evacuating said chamber to raise liquid therein to a level above the intake passage thereby to prime the pump, said evacuating means comprising a vacuum tank connected to said chamber, and a pump for creating a partial vacuum in said tank; means for closing the connection between the chamber and vacuum tank when the liquid rises to a predetermined level in said chamber; means for stopping the action of the vacuum pump when the vacuum in the tank is substantially higher than the vacuum corresponding to rise of liquid to said predetermined level; and means connected to said chamber and continuously subjected to an ejector action of

5 liquid being handled by the centrifugal pump to effect continuous removal of gas accumulating in said chamber and to maintain at least said predetermined level of liquid therein.

12. In combination, a centrifugal pump; means providing a chamber connected to the intake passage of the centrifugal pump; means for evacuating said chamber to raise liquid therein to a level above the intake passage thereby to prime the pump; means for stopping the evacuating action of the last means when the liquid has been so raised; and means connected to said chamber and subjected to an ejector action of liquid being handled by said pump to maintain a partial vacuum in said chamber after evacuation by said evacuating means ceases, said last means comprising a tube opening closely adjacent the shaft of said pump and subjected to the ejector action of liquid adjacent said shaft.

13. In combination, a centrifugal pump comprising a casing having intake and discharge passages, a rotor, and a shaft carrying the latter; means providing a chamber connected to the intake passage of the centrifugal pump; and means connected to said chamber and subjected to an ejector action of liquid being handled by said pump to cause rise of liquid in said chamber, said last named means comprising a tube opening closely adjacent the shaft of said pump at the intake side of the rotor and subjected to the ejector action of liquid rotating adjacent said shaft.

14. In combination, a centrifugal pump comprising a casing having intake and discharge passages, a rotor, and a shaft carrying the latter; means providing a chamber; means connecting a lower portion of the chamber to the intake passage of the centrifugal pump; and additional means connecting the chamber to the intake passage of the centrifugal pump comprising a tube communicating with the upper portion of said chamber and opening closely adjacent the shaft of said pump and subject to the ejector action of liquid rotating adjacent said shaft.

FRANK S. BROADHURST.
